BEVERAGE BOTTLE CARRYING CASE

John A. Gale, Wayzata, Minn., assignor to Sinclair-Koppers Company, a partnership of Delaware

Filed Aug. 3, 1966, Ser. No. 3,328

Term of patent 14 years

(Cl. D58—26)

The figure is a perspective view of a beverage bottle carrying case showing my new design as seen from the front and side. The rear of the article is identical in appearance to the front, and the side away from the side shown in the drawing is identical in appearance to the side shown in the drawing.

I claim:

The ornamental design for a beverage bottle carrying case, as shown and described.
